SIGNALING SYSTEM

Filed Sept. 7, 1922

2 Sheets-Sheet 2

Fig. 6.

UNITED STATES PATENT OFFICE.

ELY M. T. RYDER, OF YONKERS, NEW YORK.

SIGNALING SYSTEM.

Application filed September 7, 1922. Serial No. 586,563.

To all whom it may concern:

Be it known that I, ELY M. T. RYDER, a citizen of the United States, residing at Yonkers, in the county of Westchester and 5 State of New York, have invented certain new and useful Improvements in Signaling Systems, of which the following is a specification.

One of the objects of my invention is the 10 provision of a signal system in which a plurality of visible signals are used which are selectively operated in predetermined groups.

Another object of my invention is the provision of a novel form of switch member 15 which controls the visible signals through one kind of movement, and which preferably controls a signal unit of another character through a different kind of movement.

My invention consists of certain novel 20 parts and combinations of parts particularly pointed out in the claims.

The following is a description of a signaling system embodying my invention in the 25 form at present preferred by me, but it will be understood that various modifications and changes may be made therein without departing from the spirit of my invention and without exceeding the scope of my claims.

My invention will best be understood by 30 reference to the accompanying drawings, in which Figure 1 is a rear view of a vehicle showing two groups of lamps operated in accordance with my invention; Fig. 2 is a diagrammatic view illustrating the switch member and showing the circuit connections; Fig. 3 illustrates diagrammatically the groups of visible signals which are given 35 in different positions of the switch member and for parking; Fig. 4 is a horizontal section through the switch member; Fig. 5 is a vertical sectional view taken along the line 5-5 of Fig. 4; Fig. 6 shows the contacts of one-half of the stationary part of the switch member developed, and Figs. 7 to 11 illustrate diagrammatically different arrangements for the various positions of the controller.

Like reference characters indicate like 40 parts throughout the various views.

Referring, now, to the drawings in which I have shown one embodiment of my invention, I have indicated, generally, at 10 in 45 Figs. 1 and 2 and at the rear of the vehicle,

a group of five visible signals which are here 55 illustrated as lamps 10^a, 10^b, 10^c, 10^d and 10^e, which are preferably arranged side by side, and which are preferably of alternately different colors, the lamps 10^a, 10^c and 10^e preferably being red, while the lamps 10^b and 10^d are preferably green. The different colors 60 may be secured by using lamps with different colored bulbs or by using white bulbs and different colored lenses. I have also indicated at 11 a second group of lamps similar to the rear group which may be located 65 at the front of the vehicle, and which are operated with the first group of lamps and which are here shown as connected in parallel with the respective lamps of the rear group 10, so that the front lamps are operated 70 in the same combinations as are the rear lamps. The lamps are mounted on a vehicle which I have indicated, generally, at A, the body of which is indicated at 12, the wheels at 13, the rear axle at 14 and the rear 75 mud guards at 15.

The switch member or circuit controller 80 which I have indicated, generally, at B, is preferably mounted on the steering post 16 of the vehicle. The switch member, which I have here illustrated, comprises a part 17 85 which is stationary with respect to the steering post 16, and a part 18 which is rotatable with respect thereto and which is also preferably movable axially thereof. The stationary part of the switch member preferably comprises a series of contacts indicated, generally, in Fig. 2 at 19, and preferably comprising three spaced contacts 19^a, 19^b and 19^c, the contacts 19^a and 19^c preferably 90 being of sufficient length to extend through two successive positions of the rotary part of the switch member, the intermediate contact member 19^b preferably being shorter than the other two. The contact members 19^a, 19^b and 19^c are electrically connected together, as indicated in Fig. 2, and are connected to one terminal of a battery 20, the opposite terminal of which is preferably 95 grounded at 21. The rotary portion of the switch member comprises a contact arm, indicated, generally, at 22, which extends on opposite sides of the member on which it is mounted, one end 23 of the contact arm being provided with a contact member 24 100 which engages stationary contact members 105

19^a, 19^b and 19^c when brought to a position opposite the same. The opposite end 25 of the contact arm 22, cooperates with a plurality of series of contact members which are indicated, generally, at 26, 27, 28 and 29 and which are preferably vertically spaced, as indicated in Fig. 5. The contact member 26 preferably comprises three short spaced contact members 26^a, 26^b and 26^c, located at 10 the "back", "ahead" and "stop" positions of the controller. The contact 27 comprises a short contact 27^a located at the "back" position, and a contact piece 27^b, extending over the "right" and "stop" positions. The contact 15 28 preferably comprises a long contact member 28^a, extending over the "back" and "left" positions and a short contact member 28^b located at the "stop" position. The contact member 29 comprises a long contact member 29^a extending over the "back" and "left" positions, an intermediate contact member 29^b at the "ahead" position, and a contact member 29^c at the "stop" position. The contact members 26 are connected by a 20 conductor 30 to one terminal of each of the middle red lamps 10^c and 11^c of the two groups 10 and 11, respectively, the opposite terminals of which are connected through a common conductor 31 to the ground 32. The contact members 27 are connected by a 25 conductor 33 to one of the terminals of each of the lamps 10^a and 11^a, which are also connected by the conductor 31 to the ground, as at 32, it being understood that one terminal of each of the lamps is grounded. The contact members 28 are connected by a conductor 34 to each of the red lamps 10^a and 11^a. The contacts 29 are connected by the conductor 35 to the green lamps 10^b and 10^d 30 and to 11^b and 11^d. The end 25 of the arm 22 is provided with contact members 37, 38, 39 and 40 which engage the stationary contacts 26, 27, 28 and 29, respectively, when brought opposite the same. The contacts 26, 27, 28 and 29 are 35 preferably secured to a cylindrical insulating member 41 which is mounted within a cylindrical part 42 extending upwardly from the steering post. The rotary part 50 of the switch member preferably comprises an inverted dished member 43 having a downwardly-extending flange 43^a at the top of the member preferably being in the form of a spider from which a boss or lug 44 extends downwardly. A shell or cylinder 45 is secured to the flange 43^a, as indicated in Fig. 5, and to the lower end of the shell 45 is secured a ring 46 having a horizontally-extending flange 46^a which extends beneath the stationary part 17 of the switch member, as indicated in Fig. 5, to retain the rotary part in position, the vertical flange being secured to the cylindrical member 45, as by screws 47. The top of 55 the switch member is closed by a cover plate

48 which may conveniently be secured to the shell 45, as by screws 49, so that by removing the cover plate 48 access may be had to the operating parts of the switch through the spider formed at the top of the member 43. The rotary switch arm 22, which is preferably of the form best shown in Fig. 4, is provided with a cylindrical part surrounding an insulating sleeve 50 in turn secured to the boss 44, and is secured to said sleeve, as by screws 51. The rotary part of the switch member is normally raised to the position indicated in Fig. 5 by a leaf spring 52, the ends of which engage the outwardly-extending flange at the top of the steering post 16, as best shown in Fig. 5. A stem or plunger 53 is secured in the lower end of the boss 44 and engages at its lower end a movable switch member 54 which is normally held in the open position indicated in Fig. 5 by a spring 55. By depressing the movable part of the switch member and thereby moving it along its longitudinal axis, the switch arm 54 is brought into engagement with a stationary contact 56 and closes a circuit from a battery 57 to an electrically operated device for actuating an audible signal 58 in a well understood manner. As is evident, the rotary part of the switch may be depressed at the will of the operator to give an audible signal with the rotary member in any of its various positions.

A switch 59 (see Fig. 2) which is operated by the foot brake and which has three poles, is preferably provided, one terminal of the switch being connected by a conductor 60 to one terminal of the battery 20, the three arms of the switch member engaging stationary contacts which are connected by conductors 61, 62 and 63, respectively, to the red lamps 10^c, 10^a and 10^d. A manually operated switch 64 is also preferably provided, the movable arm of which is connected by a conductor 65 to one terminal of the battery 20, the stationary contact being connected by a conductor 66 to one of the red lamps 10^c which serves as a parking signal. It is evident that both the switch 59 operated by the foot brake and the manually operated switch 64 are connected around the controller and may be operated when the controller is in neutral position.

The shell or cylindrical member 45, consisting of a part of the rotary switch member, is preferably provided with a plurality of outwardly-extending beads 67 forming on the inner side of the shell notches which are adapted to be engaged by a detent member 68 secured to the fixed part of the switch member 17, and which is formed with a detent portion 68^a adapted to engage the notches 67 to retain the rotary part of the switch member in the various operating po-

sitions. Spring members 69, two being illustrated, are also preferably secured to the fixed part of the switch member, the springs being bent outwardly, as indicated in Fig.

5, and engaging the shell 45 to retain the rotary part of the switch member concentric with the stationary part.

A third group of lamps 70 are indicated in Fig. 1, which are mounted on the front 10 mud guard and furnish a tell-tale indication to the driver of the car, and which may be connected with respect to the lamps 10 and 11 in the same manner as are the lamps 11 with respect to the lamps 10. In order 15 to avoid confusion, I have not illustrated this third group of lamps in Fig. 2. It will, of course, be understood that as many groups of indicating lamps may be used as desired, without departing from the spirit 20 and intent of my invention.

The operation of the device illustrated will readily be understood from the foregoing description and is as follows:

When the rotary member occupies the 25 neutral position indicated in Fig. 2, it will be evident that none of the contacts of the rotary member are in engagement with the stationary contacts and no lamps are lighted. By moving the controller to the left 30 to the position indicated "Ahead", the movable contact member 24 will engage the stationary contact member 19^b and the movable contact members 37 and 40 will engage the stationary contact members 26^b and 35 29^b, respectively, thereby closing a circuit from the ground 21 through the battery 20, through the contact members 19^b and 24, and through the members 40 and 29^b to both of the green lamps 10^b and 10^a, and also 40 through the contact members 37 and 26^b and through the middle red lamp 10^c to the ground, thus lighting the two green lamps and the middle red lamp, thereby indicating 45 by the position of the red lamp with respect to the two green lamps that the vehicle is intending to go straight ahead. Such a signal is particularly valuable as affording an indication to a traffic officer as to the direction that the vehicle desires 50 to proceed. By moving the controller to the position "Right", it will be evident that both green lamps and the red lamp at the right are lighted by circuits which will readily be traced. By moving the switch 55 member still further to the right to the position "Stop", the three red lamps will be lighted. When the controller is moved to the left of neutral position to the position indicated "Left", the two green lights and 60 the red lamp at the left are lighted, and when it is moved still further to the left to the position indicated "Back", all five of the lamps are lighted. It will thus be apparent 65 that the five lamps comprised with in my invention are operated in predeter-

mined groups to afford indications of the movement of the vehicle, and particularly affords an indication, by the position of a single lamp of one color with respect to two lamps of another color, of the direction in 70 which the vehicle is going to move. The order of the positions occupied by the movable part of the controller can be variously arranged, as indicated in Figs. 7, 8, 9, 10 and 11.

When the movable switch controller is in the neutral position, it will be evident that the operation of the foot brake will give a stop signal and that the hand switch may be operated to give a parking signal. 75

I claim:

1. A vehicle signaling system comprising at least five lamps arranged substantially horizontally and in alinement and side by side and of alternately different colors, there 85 being three lamps of one color and two lamps of a second color, the end lamps being of the same color, and a switch and associated connections for simultaneously operating the two lamps of the second color and either of said end lamps to afford an indication by the position of the second lamp with respect to the other two of the movements of a vehicle.

2. A vehicle signaling system comprising 95 at least five lamps arranged substantially horizontally and in alinement and side by side and of alternately different colors, there being three lamps of one color and two lamps of a second color, the end lamps 100 being of the same color, and a switch and associated connections for simultaneously operating the two lamps of the second color and either of said end lamps to afford an indication by the position of the second lamp 105 with respect to the other two of the movements of a vehicle and for simultaneously operating the three lamps of the first color only to afford an indication of a change of speed of the vehicle. 110

3. A vehicle signaling system comprising at least five lamps arranged substantially horizontally and in alinement and side by side and of alternately different colors, there 115 being three lamps of one color and two lamps of a second color, the end lamps being of the same color, and a switch and associated connections for simultaneously operating the two lamps of the second color and either of said end lamps and for simultaneously operating the two lamps of the second color and the intermediate lamp of the first color to afford an indication by the position of one of the second lamps with respect to the other two of the movements 120 of a vehicle. 125

4. A vehicle signaling system comprising at least five lamps arranged substantially horizontally and in alinement and side by side and of alternately different colors, there 130

being three lamps of one color and two lamps of a second color, the end lamps being of the same color, and a switch and associated connections for simultaneously operating the two lamps of the second color and either of said end lamps to afford an indication by the position of the second lamp

with respect to the other two of the movements of a vehicle, and for simultaneously operating all of the lamps to afford an indication of a different character of movement of said vehicle. 10

ELY M. T. RYDER.
